PUMP

Herbert R. Lafferty, Davenport, Iowa, assignor to
Red Jacket Mfg. Co., Davenport, Iowa, a corporation of Iowa

Application December 29, 1934, Serial No. 759,705

2 Claims. (Cl. 74—50)

This invention relates to improvements in hydraulic pumps, and more particularly to reciprocating water pumps of the shallow-well type, and has for its principal objects to produce a simple and economical construction for devices of the character described.

In carrying out my invention, I provide an improved form of double acting pump including a crank case and pressure chamber formed integrally with the main frame casting and arranged so the pump cylinder and plunger bearings are in alignment with each other so as to be machined in a single operation. I also provide a novel drive for the plunger, and improvements in valve construction, all of which will appear in greater detail in the following description:

The invention may best be understood by reference to the accompanying drawings, in which

Fig. 1 is a fragmentary side view of a pump in accordance with my invention, with the crank case and pressure chamber shown in section.

Fig. 2 is an enlarged detail section taken generally on line 2—2 of Fig. 1.

Fig. 3 is a section taken on line 3—3 of Fig. 2.

Fig. 4 is a detail section taken on line 4—4 of Fig. 1.

Fig. 5 is a detail perspective view of the plunger drive yoke.

Fig. 6 is an enlarged detail of the valve and valve stem mounting.

Referring now to details of the embodiment of my invention illustrated in the drawings, the main parts of the pump consist of a base 10 having a pump housing 11 and a crank case 12 cast integrally therewith in horizontally spaced relation, and also forming a support for a motor 13 suitably mounted above the crank case 12 as shown.

The pump housing 11 has a cylinder 15 cast integrally therein, and lined with a sleeve 16 within which the plunger 17 is reciprocably mounted. The housing 11 is divided by vertically disposed webs 18 and 19 above the cylinder and merging into a web 20 below said cylinder, so as to form two pressure chambers 21 and 22 communicating respectively with opposite ends of the cylinder 15. The housing 11 has an aperture 28 at its outer end, closed by a plate 28a.

Each of the pressure chambers is provided with a set of inlet and outlet valves. In the form shown, the inlet valves 23, 24 are mounted on a horizontal web 25 spaced below the cylinder 15 and forming a partition for an inlet passage 26 suitably communicating with the exterior of the housing 11.

Outlet valves 23a and 24a are mounted on hori-

zontal webs 18a and 19a which form continuations of the vertical webs 18 and 19, respectively, above the cylinder 15, and provide a partition for the outlet chamber 27 at the top of the housing 11. Said outlet chamber has an outlet passage indicated at 27a and suitably communicating with the exterior of the housing. A pressure dome 29 is connected with the outlet chamber 27 in the usual manner.

The inlet and outlet valves are all of the poppet type, each including a circular valve plate 30 preferably having a facing piece 31 of suitable semi-yielding material such as moulded rubber, and adapted to close the aperture in valve seat 32 as is best seen in Fig. 6. The valve stem 33 is supported in a novel manner, independently of the valve seat 32, by fixing the end which projects through the valve seat to a pin 34 mounted on an adjacent abutment, as for instance, the wall of the cylinder 15. The opposite end of said stem has a head 35, with a coil spring 36 engaged between said head and the valve plate 30 so as to maintain the valve normally in closed position against the valve seat. With the valve construction above described, the valve stem is supported independent of the valve seat so as to eliminate the usual form of valve seat including webs for supporting said stem directly on said seat, which latter construction restricts the effective area of the valve aperture. The improved form of valve seat 32 disclosed herein may therefore consist of a plain ring, pressed or otherwise mounted in its supporting partition.

The valves are rendered accessible for inspection and repair by valve plugs 38, 38 threaded in the outer walls of the housing 11 over each of said valves. Said plugs are preferably recessed so as to receive the upper ends of the adjacent valve stem, as shown. It will be especially noted that the two plugs 38, 38 at the bottom of the casing serve as removable traps for sand and dirt, and also as a means of draining the entire pump housing, when desired.

The plunger 17 has a plunger rod 17a which passes through a packing gland 39 of the usual form at the inner end of the housing 11. Said gland is herein formed as a separate piece pressed or otherwise mounted in the end wall of said housing.

The crank case 12 contains the driving mechanism for converting the rotary motion of the main drive shaft 40 to reciprocating motion of the plunger rod 17a. The drive shaft is suitably driven by the motor 13, as by the usual belt and pulley drive (not shown). As herein illustrated

in Fig. 2, the shaft 40 has bearing support at only one side of the casing 12, by means of an elongated bearing member 41 detachably secured to the casing, and having bushings 42, 43 mounted in spaced relation therein. The bearing member 41 is provided with suitable oil ducts 44, 45 for supplying lubrication to the outer end of the outer bushing 43 from the interior of the casing.

10 The shaft 40 has a disc 46 fixed on its inner end forming a crank member having a crank pin 48 mounted on the outer face of said disc. Said crank pin extends into a block 49 slidably mounted between guides 49^a, 49^b of a vertically disposed 15 yoke 50 supported on the plunger rod 17^a, as clearly shown in Figs. 2, 3 and 4. The plunger rod 17^a extends through a bearing 52 at the inner end of the casing, and has its opposite end guided in a detachable bearing cap 53 at the 20 opposite or outer end of said casing. With this arrangement, the yoke 50 is held in bearing engagement with the inner face of the disc 46 so as to be supported in upright position thereby without any additional guiding means in said casing. 25 The block 49 is also retained in its slot by lateral engagement with the disc 46. This construction is in effect a simplified form of Scottish yoke, by which rotation of the shaft 40 and disc 46 will produce reciprocation of the plunger rod 17^a. 30 The crank case 12 is preferably enclosed and partially filled with oil so that the moving parts may be thoroughly lubricated. In order to assist in lubricating the plunger rod bearings 52 and 53 at the ends of said casing, I provide a pair of 35 deflector blades 55, 55 extending from opposite sides of the yoke 50 near the top thereof, said blades being inclined downwardly and away from points adjacent the plane of rotation of the disc 46 and having their outer ends in position to 40 pass over oil holes 52^a and 53^a formed in the inner sides of the plunger rod bearings 52 and 53, respectively, when said yoke reaches the end of its stroke in either direction. With this arrangement, oil will be splashed on the blades 55 45 from the rotating disk 46 or flow from the top of yoke 50, and drop into the oil holes 52^a and 53^a from time to time, to lubricate these bearings. For simplicity in construction, the inner bearing 52 is a plain bronze bushing, providing a running fit for the plunger rod, but it will be understood that said bearing may be provided with a packing gland of the usual form, if desired. A leather washer 56 is mounted on the plunger rod between the casing 12 and pump housing 11, to 50 keep water from being carried along the plunger and into the casing 12.

With the construction above described, it will now be understood that the pump may be manufactured most economically. The housing 11 and crank case 12 are in horizontal alignment with each other so that the cylinder 15 and the bores for the packing gland 39 and plunger bearing 52 may all be machined in a single operation, from either end of the casing. The Scottish yoke device in the casing 12 is of especially simple construction, in which the main drive shaft 40 has bearing support in one side wall only of the casing 12, and the yoke 50 has no vertical guide means in said casing, but is held in upright position through its bearing against the disc 46. The parts are all readily accessible for inspection, repair or replacement.

Although I have illustrated and described one particular embodiment of my invention, it will be understood that I do not wish to be limited to the exact construction shown and described, but that various changes and modifications may be made without departing from the spirit and scope of my invention as defined in the appended claims.

I claim:

1. In a pump, an enclosed crank case adapted to contain lubricant, a horizontally reciprocating plunger having a bearing guide at the ends of said casing, an enlarged yoke fixed on said plunger, a block guided for reciprocation in said yoke vertically of said plunger, a crank member rotatably supported in said crank case, and including a crank pin having lateral engagement with said block to form the sole means for maintaining said yoke and block in operative position parallel to the plane of rotation of said crank member, and means carried by said yoke for directing lubricant from the upper portion of said yoke and feeding it by gravity to the bearing guide of said plunger when said yoke approaches the limit of its stroke.

2. In a pump, an enclosed crank case adapted to contain lubricant, a horizontally reciprocating plunger having bearing guides at opposite ends of said casing, an enlarged yoke fixed on said plunger, a block guided for reciprocation in said yoke vertically of said plunger, a disc rotatably supported in said crank case and including a crank pin having lateral engagement with said block, and a projection carried on the upper portion of said yoke for directing lubricant laterally and downwardly to feed it by gravity to the adjacent bearing guide of said plunger when said yoke approaches the limit of its stroke.

HERBERT R. LAFFERTY.
